UNITED STATES PATENT OFFICE.

WILLIAM J. MORSE, OF ATTLEBORO, MASSACHUSETTS.

BELT BUCKLE.

Application filed September 18, 1925. Serial No. 57,106.

This invention relates to an improved construction of belt buckle of the tongue variety employed more particularly for retaining a belt in adjusted position about the 5 waist of the wearer. One object of this invention being to provide such a buckle having a body frame portion to which the tongue member is hinged and to provide a belt-guiding loop on the frame, of such a 10 width as to receive a belt wide enough to cover the frame so that the frame portion will not be exposed when the belt is positioned in the buckle.

A further object of the invention is to 15 mount a guide loop on the frame having a broad face for the purpose of receiving ornamentation.

A still further object of the invention is to pivot the guide loop on the buckle frame 20 and to mount a tongue releasing finger to be operated by the pivotal movement of the guide to move the tongue from engagement with the belt.

With these and other objects in view, the 25 invention consists of certain novel features of construction, as will be more fully described, and particularly pointed out in the appended claims.

In the accompanying drawings: 30 Figure 1 is a front view of a belt on which my improved buckle is mounted.

Figure 2 is a section on line 2—2 of Figure 1, illustrating the general positions of the different parts of the buckle relative to 35 the belt.

Figure 3 is a section on line 3—3 of Figure 1 showing the belt guiding loop as secured to the body frame of the buckle.

Figure 4 is a perspective view of the underside of my improved buckle.

Figure 5 is a perspective view of the underside of the base portion of the loop member.

Figure 6 is a perspective view of the underside of the top portion of the loop member, removed from its base portion.

Figure 7 shows the buckle partly in section with the belt dotted in released position therethrough, showing the loop member as 50 being tipped back and the tongue operating finger as having lifted the tongue from engagement with the hole in the belt.

It is found of advantage in the construction of belt buckles of the tongue variety, 55 particularly where used on the wider types

of belts, of advantage to so form the body or frame portion of the buckle that it will be covered by the belt when in operative position thereon; also to provide a belt guiding loop on the buckle frame of a width as 60 great or greater than that of the frame portion so as to receive a belt of a width which will cover the frame; also to provide a belt-guiding loop having a broad exposed surface which is adapted to receive ornamentation. In some instances, it is also found of 65 advantage to form the belt-guiding loop of a separate piece of metal and to provide bendable portions on the loop to be pivotally connected to the frame of the buckle 70 and also to provide a finger on the buckle to be operated by the pivotal movement of the guide so that this movement will release the tongue from engagement with the holes in the belt, by which construction this type 75 of buckle which has heretofore been considered unsightly is now considered ornamental which effect is obtained by covering a portion of the buckle by the belt and exposing 80 only the ornamental guide loop thereof; and the following is a detailed description of the present embodiment of my invention and showing one construction by which these 85 advantageous results may be accomplished:—

With reference to the drawings, 10 designates the body frame of my improved buckle, which may be struck from sheet stock into the form best illustrated in Figure 4, having a cross bar 11 at one end notched as at 12, around which the end portion 13 of the 90 tongue 14 is looped and also to which one end of the belt 15 is fixed.

A belt guide loop member 16 is herein shown as being formed of sheet stock having downwardly turned side wall portions 17, 95 which portions are provided with bendable fingers 18. In order to pivotally mount this loop member upon the cross bar 19 of the buckle frame, I have formed a base member 20, as best illustrated in Figure 5, the same having tapered side walls 21 which fit in between the side walls 17 of the loop member and is secured to the loop member by the folding of the fingers 18 inwardly about these tapered side walls 21.

In order to pivotally mount this base member and the loop member upon the cross bar 19 of the body of the buckle, I have rolled one edge of the stock of this base member as at 22 about the cross bar 11,

thereby permitting the guide loop to swing on this cross-bar as a pivot.

It is found in practice that if the broad faced guide loop member is rigidly mounted upon the cross bar 19 that, in some instances, it is slightly difficult to release the tongue 14 from the engaged hole in the belt 24 unless the belt is drawn endwise through the loop in a direction to tighten the same about the body. Therefore to provide simple and effective means for releasing this tongue from engagement with its hole in the belt without the necessity of an endways tightening movement of the belt, I have fixed a tripper finger 25 on the base member 20 to extend forwardly into engagement with the underside of the tongue 14, whereby a simple releasing movement of the belt-end 26, as illustrated in dotted lines in Figure 7, serves to swing the guide loop on its pivot bar 19 and at the same time brings the releasing finger 25 into engagement with the tongue 14 to withdraw the tongue from the hole 23 and permits the belt to be freely withdrawn from the buckle.

It will be seen by my improved construction that I have notched as at 27 the rolled portion 22 of the base member so as to provide a stop or limit for the backward swing of the loop 16 thereby causing the tongue-lifting finger to prevent the tongue 14 from dropping down between the arms 10 of the frame, which would be the case if the loop member were permitted to swing without a proper limiting stop, thus insuring the parts returning to their proper positions after the belt releasing movement.

It is clearly herein shown that the tongue 14 of the buckle is of a length after passing through the hole 23 in the belt to lie against the upper face of the guide loop plate to form a rest or stop for the tongue when the loop plate is in its normal or working position.

It will be noted that the width between the inner surface of the side walls 17 of this belt-guiding loop is as great or greater than the width of the body frame at its widest point so as to receive a belt which is sufficiently wide to cover the buckle frame beneath it, which, of course, is narrower than the belt.

My improved buckle is very simple, practical and inexpensive to construct yet when positioned on a belt the heretofore unsightly portion of the buckle is entirely covered by the belt, exposing only a band or looped portion which serves as an ornament for the belt.

The foregoing description is directed solely towards the construction illustrated, but I desire it to be understood that I reserve the privilege of resorting to all the mechanical changes to which the device is susceptible, the invention being defined and

limited only by the terms of the appended claims.

I claim:

1. A belt buckle having a body frame, a separate plate having rearwardly extending portions forming a guide, said plate being attached to one end of the frame and said plate presenting a broad front surface spaced above and lying in a plane substantially parallel to the plane of said frame when in working position, and a tongue hinged to said frame at the opposite end thereof and extending to rest on said broad surface.

2. A belt buckle having a body frame, a sheet metal plate folded to form a guide and pivotally mounted on the frame intermediate the end of said plate, said plate being spaced above the frame to receive the belt and having a broad front surface to receive ornamentation, a tongue to engage an opening in the belt, pivoted to said frame and extending toward and of a length to rest on said broad surface.

3. A belt buckle having a body frame, a tongue member hinged to one end of the frame, a plate folded to form a belt guide with a broad surface carried by the opposite end of said frame and located above the same and having a belt-receiving opening of a width approximately that of said frame and forming a rest for the free end of its tongue in combination with a belt of a size to fit said opening and extending therethrough whereby this belt covers the top of the frame to hide the same.

4. In combination with a belt, a tongue buckle attached to one end thereof and comprising a frame of a width less than the free end portion of the belt, a tongue on said frame, and a loop member for receiving and guiding the free end of the belt over said frame, whereby the frame is hidden from view by the belt.

5. In combination with a belt, a buckle attached to one end thereof said buckle comprising a frame, a separate guide loop raised from and mounted on the front surface of the frame and of a width as great as that of the frame and through which the free end of the belt may extend over the front of said frame, a tongue on the frame to extend through a hole in the free end portion of the belt, said belt being of a width greater than said frame to hide the same from view.

6. In combination with a belt, a tongue buckle attached to one end thereof and comprising a frame of a width less than the free end portion of the belt, a tongue on said frame, and a sheet metal loop member for receiving and guiding the free end of the belt over said frame, whereby the frame is hidden from view by the belt, said loop having a portion folded about said frame to connect the two together.

7. A belt buckle comprising a substantially rectangular frame of sheet metal, a tongue for extending through the free end portion of said belt and hingedly mounted at one end of said frame, a sheet metal guide loop for the free end of the belt and having portions folded about the opposite end of said frame to secure the same thereto, said loop having a broad front surface for the reception of ornamentation and to be engaged by the free end of said tongue, said surface being mounted in a plane spaced above but substantially parallel with the plane of said frame.
8. In combination with a belt having a narrowed end portion, a buckle having a substantially rectangular body frame of a width less than the normal width of the belt and to one end of which said narrowed end portion is permanently attached, a tongue hinged to said frame and protruding through said narrowed end portion, a belt loop of a width to receive the free end of the belt carried by the opposite end of said frame and forming a rest for the free end of said tongue whereby the normally wide portion of the belt extends through the loop and over the frame to cover the frame leaving only the loop exposed to view.
9. A belt buckle having a frame portion, a belt-engaging tongue pivotally mounted on the frame, a belt guide pivotally mount-
- ed on the frame, and a means responsive to the pivotal movement of said guide for engaging the tongue and moving it from engagement with the belt. 35
10. A belt buckle having a frame portion, a belt-engaging tongue pivotally mounted on the frame, a belt guide pivotally mounted on the frame, and a member carried by the guide positioned to swing into engagement with the tongue and disengage it from the belt upon a pivotal movement of the guide. 40
11. A belt buckle having a frame portion, a belt-engaging tongue pivotally mounted on the frame, a belt guide pivotally mounted on the frame, a member carried by the guide to be operated by the pivotal movement thereof to move the tongue from engagement with the belt, and a stop for limiting the tongue-releasing movement of said guide and member. 45
12. A belt buckle having a frame portion, a belt-engaging tongue pivotally mounted on the frame, a belt guide pivotally mounted on the frame and of a width to receive a belt to cover said frame, and a member connected to said guide of a length to engage the tongue to move it to disengage the belt upon a pivotal movement of said guide. 50
